H. HOWSON.

Car-Axle Box.

No. 21,998.

Patented Nov. 2, 1858.

UNITED STATES PATENT OFFICE.

HENRY HOWSON, OF PHILADELPHIA, PENNSYLVANIA, ASSIGNOR TO ISAAC P. WENDELL
AND JACOB L. WENDELL, OF SAME PLACE.

AXLE-BOX.

Specification of Letters Patent No. 21,998, dated November 2, 1858.

To all whom it may concern:

Be it known that I, HENRY Howson, of the city of Philadelphia and State of Pennsylvania, have invented certain new and useful Improvements in Axle-Boxes; and I do hereby declare the following to be a full, clear, and exact description of the same, reference being had to the accompanying drawing and to the letters of reference 10 marked thereon.

My invention consists in a combination of a box, bearings and keys, the interior of the box being arched and terminating on each side at recesses formed in the sides of the 15 box, the keys being adapted to fit into recesses and against the edges of the bearings, and the several parts being arranged, in respect to each other, substantially in the manner fully set forth hereafter.

20 The object of my invention is to produce a box of light and simple form, and one from which the bearings can be readily removed by raising the box to the slightest extent, and into which the axle as well as 25 the bearings may be introduced with facility.

My invention has the further advantage of allowing the center of the axle to be nearer to the top of the box, than in ordinary axle boxes.

In order to enable others skilled in the art to make and use my invention, I will now proceed to describe its construction and operation.

35 On reference to the accompanying drawing, which forms a part of this specification; Figure 1, is a longitudinal section of an axlebox with my improvements, which are adapted to the improvements in axles 40 and boxes, for which a patent was granted to Isaac P. Wendell on the second day of

March 1858. Fig. 2, a front view of Fig. 1, with the cover plate removed. Fig. 3, a sectional plan on the line 1, 2, (Fig. 1). Fig. 45 4, a transverse section on the line 3, 4, (Fig. 1) with both keys removed. Fig. 5, a section on the line 5, 6, (Fig. 4). Fig. 6, a section on the line 7, 8, (Fig. 1). Fig. 7, a longitudinal section of an axle box with my 50 improvements, adapted to an axle of the ordinary construction. Fig. 8, a transverse section on the line 9, 10, (Fig. 7) with one of the keys removed. Fig. 9, a section on the line 11, 12, (Fig. 7). Fig. 10, a longi-

tudinal view of one of the keys. Fig. 11, a 55 diagram illustrating a modified form of box and bearing with my improvements.

Similar letters refer to similar parts throughout the several views.

A is the body of the box, having on each 60 side the usual guides a, a, adapted to the hanger of the car, the lower portion b of the box forming the receptacle for the oil or other lubricating matter.

B and B' are two separate bearings, 65 adapted to and fitting against the arched interior of the box, their upper ends fitting against the separating lug c, projecting from the center of the arched interior, and being retained in their proper positions by 70 the keys C and C', the latter bearing at the top against the ledges d, d, formed at the termination of the arched interior of the box, at the bottom against the ledges e, e, which form the upper termination of the 75 oil cup, and also against the sides g, g of the recesses formed in the box for the reception of the said keys. The bearings B and B' are retained in their proper, longitudinal position, in front by the lips f, f, projecting 80 from the arched interior, and at the back by bearing against the inside end of the box. The bearings may be constructed of any of the materials usually used for the purpose. When adapted to Wendell's improvement, 85 however, they must have recesses i for the central collar j, as illustrated in Fig. 5. But when adapted to ordinary axles, as shown in Fig. 9, the bearings may be free from such recesses and uniform throughout.

90 The keys may be of any form desired, provided they have the bearing points above described, the form illustrated being adopted for the sake of lightness.

The keys are retained in their places at 95 the back, by bearing against the inside end of the box, and in front by the cover plate D.

It should be understood, that the space occupied by each key must be sufficient in height and width to allow (when the key is removed) one of the bearings to be drawn laterally, in the first instance, clear of the central collar j, or of the external collar j, (Fig. 7) and be subsequently drawn out longitudinally clear of the box.

100 The packing arrangement is constructed as follows: A recess is formed at the back of the box by the two ribs k and k', the lower

portion of this recess being semicircular, and the upper portion parallel and open at the top for the admission of the follower F, as seen in Fig. 6, the lower end of this follower 5 being of a semicircular form or thereabout. Two lugs m, m, project from the top of the box, one on each side, and into these lugs screw the stud bolts n, n, which pass freely through the lugs p, p, on the follower, so 10 that the latter may be depressed at pleasure. In the bottom of the curved portion of the recess, I deposit three curved wedges q, q and r, the latter tapering from the middle toward each end, one endlapping over the 15 end of one of the wedges q, and the other lapping over the end of the opposite wedge. Sufficient space is left between the semicircular end of the follower F and the axle E, as well as between the wedges and the axle, 20 to admit the packing t.

Supposing that the bearings B and B' and the keys C and C' to be in their proper position, as seen in Fig. 2, and that it is necessary to remove the bearings from the box, 25 The cover D having been previously unscrewed, the box is raised to a very slight extent, sufficient only to remove the pressure from the bearings B and B'. The keys C and C' are now drawn out, when the opposite bearings at once drop down, free from the retaining lips f. The bearings are then drawn laterally clear of the collar on the axle, so as to assume the position shown in 30 Fig. 4. They may then be readily pulled out

clear of the box. It will be easily seen, that 35 they may be as readily replaced.

The advantages gained by the above described mode of removing and replacing the bearings, may be briefly enumerated as follows: First, the box requires but the slight- 40 est lift, prior to effecting this desired removal. Second, the center of the axle is nearer to the top of the box than in ordinary boxes. Third, the general arrangement is much more simple than in other boxes. 45 Fourth, the axle and bearings are removed and replaced with the greatest facility.

I claim and desire to secure by Letters Patent—

The combination of the box with the bearings B and B' and retaining keys C and C', when the interior of the box is arched on the top, when the said arch terminates on each side at the recesses g, g formed in the sides of the box, when the keys are adapted to fit 50 into the recesses and against the edges of the bearings, and when the several parts are arranged, in respect to each other, substantially in the manner and for the purpose 55 herein set forth.

In testimony whereof, I have signed my name to this specification before two subscribing witnesses.

HENRY HOWSON.

Witnesses:

WILLIAM H. BROWN,
HENRY ODIORNE.
